UNITED STATES PATENT OFFICE.

WARREN CHAMBERS, OF BELOIT, WISCONSIN.

GRINDER FOR PACKING-RINGS FOR PISTONS.

SPECIFICATION forming part of Letters Patent No. 793,276, dated June 27, 1905.

Application filed August 12, 1904. Serial No. 220,553.

To all whom it may concern:

Be it known that I, WARREN CHAMBERS, a citizen of the United States of America, residing at Beloit, in the county of Rock and 5 State of Wisconsin, have invented certain new and useful Improvements in Grinders for Packing-Rings for Pistons, of which the following is a specification.

The object of this invention is the production of a grinding-machine for shaping the peripheries of metallic packing-rings of the pistons of cylinders of steam, gas, gasolene, and other engines, &c., to adapt them to fit the interiors of their respective cylinders as 15 nicely as possible; and it consists, essentially, of a circular holder for supporting and maintaining piston-rings as near as may be in the form of a true circle while they are being fitted by grinding, mechanism for rotating 20 the rings as they are being ground, and an emery-wheel or other suitable grinding means for grinding such rings as they are being rotated in the holder of the machine.

Referring to the accompanying drawings, 25 which form a part of this specification, Figure 1 is a top plan view of a machine embodying my invention. Fig. 2 is a section at the dotted line 2 2 in Fig. 1 of parts there shown. Fig. 2^a is a right-hand end view of the machine as seen in Fig. 2. Fig. 3 is a left-hand 30 end view of the machine with the base of its frame broken away. Fig. 4 is a side view of a section of a cylinder adapted to be cut into packing-rings for pistons. Fig. 5 is an end view of a packing-ring after it has been cut from the cylinder shown in Fig. 4 and severed at its thinnest part. Fig. 6 is a side view of the ring shown in Fig. 5.

Like letters of reference indicate corresponding parts throughout the several views.

The main frame of the machine is formed, preferably, by casting and may consist of a base portion A, supporting a horizontal table A', which carries an upper supporting-frame A², having horizontal shaft-bearings A³ and a vertical shaft-bearing A⁴ therein.

B is a shaft mounted in the horizontal bearings A³ in the frame A² and provided at one end with a worm B'.

B² is an emery-wheel or other suitable grinding-wheel fast-mounted on the shaft B. 50

B³ is a driving-pulley, also fast-mounted on the shaft B.

C is a vertical shaft mounted in the bearing A⁴ in the frame A². 55

C' is a worm-wheel fast-mounted on the upper end of the shaft C and meshing with the worm B' on the shaft B.

C² is a worm fast-mounted on the lower end of the shaft C. 60

D is a carriage slidably mounted on the machine-frame A and supporting a bracket D', which has a vertical shaft-bearing D² therein and also serves as a support for parts to be described hereinafter. 65

D³ is a screw of the usual well-known variety for slidably adjusting the carriage D and parts supported thereby.

E is a circular ring-holder having its side E' adjacent to the grinding-wheel B² sectioned 70 away and provided with a horizontal ring-seat E² and rigidly secured to the bracket D'.

F is a shaft mounted in the vertical bearing D² in the carriage D.

F' is a finger fast-mounted by its inner end 75 to the upper end of the shaft F and having its outer end F² adapted to engage and rotate piston-rings to be described hereinafter.

G is a bevel-gear fast-mounted on the lower end of the shaft F. 80

H H' are two members of a shaft telescopically connected by means of the sliding parts H² and mounted in bearings H³ H⁴, the former in the main frame of a machine and the latter in the carriage D. 85

I is a bevel-gear mounted on the outer end of the shaft member H and meshing with the corresponding bevel-gear G on the finger-shaft F.

J is a worm-wheel fast-mounted on the 90 shaft member H' and meshing with the worm C² on the shaft C.

K is a segment of a preferably cast and turned cylinder and is adapted to be transversely cut into rings K', which are then severed, preferably obliquely, at K², the point thereon at which the metal composing the same is thinnest. A fragment of the ring K' 95

may also be cut away to form a bearing K^3 thereon for the engagement of the point F^2 of the finger F' therewith.

After a ring K' has been placed in a holder 5 E , the sole function whereof is to support and maintain such ring K' as nearly as possible in the form of a true circle while being rotated and ground, of the proper diameter to receive the same and to permit it to be rotated therein 10 by the finger F' the carriage D is slid, by means of the adjusting-screw D^3 , over toward and into slight contact with the adjacent face of the grinding-wheel B^2 , which is rapidly rotated by means of power applied to the pulley B^3 on the shaft B , the worm B' , worm-wheel C' , shaft C , worm C^3 , and worm-wheel J , meanwhile communicating therethrough very slow motion from the shaft B to the shaft H H' , which in turn communicates like motion 15 through the bevel-gears I G , shaft F , and finger F' , which also in turn very slowly rotates the ring K' on its seat F^2 until its periphery is ground by the grinding-wheel B^2 to adapt it to closely and nicely fit the interior of the cylinder for which it is destined. 20

Obviously interchangeable holders E of any desired diameter may be mounted on the carriage D , the telescopic connections H^2 between two members of the shaft H H' allowing 25 the same to lengthen or shorten, according as the carriage is slid away from or toward the grinding-wheel B^2 by means of its adjusting-screw D^3 .

What I claim as new, and desire to secure 30 by Letters Patent, is—

1. In grinders for packing-rings for pistons, in combination, a circular holder, for rotatably supporting and maintaining the packing-rings as nearly as possible in the form of a 35 true circle, means for rotating the rings in

their holder, while they are being ground, means for grinding the peripheries of the rings as they are rotated in peripheral contact with their holder, and supporting means for all of said parts, substantially as and for 45 the purpose specified.

2. In grinders for packing-rings for pistons, in combination, a main frame, a shaft mounted therein, a grinding-wheel mounted on such shaft, a circular holder, having a portion of 50 its side adjacent to the grinding-wheel sectioned away, a carriage, supporting the holder and arranged to be slid toward and away from the adjacent face of the grinding-wheel, a shaft mounted in the carriage, a finger, for rotating a ring while being ground, mounted on the shaft in the carriage, and means for rotating the grinding-wheel and finger-shafts, substantially as and for the purpose specified. 55

3. In grinders for packing-rings for pistons, in combination, a main frame, a grinder-shaft mounted therein and provided with a worm, a grinder mounted on such shaft, a carriage mounted on the main frame and slidable thereon toward and away from the grinder, a circular holder having a portion thereof adjacent to the grinder sectioned away and mounted on the carriage, a shaft mounted in the carriage, a finger mounted on the latter shaft and adapted to engage and rotate a ring in its 60 holder and a worm-gear connection between the grinder-shaft and finger-shaft, substantially as and for the purpose specified. 65

In testimony whereof I have signed my name to this specification in the presence of two sub- 70 scribing witnesses.

WARREN CHAMBERS.
